UNITED STATES PATENT OFFICE.

EDWIN CROMPTON AND CHARLES L. CROOKS, OF PUEBLO, COLORADO.

LOCK OR LATCH.

Application filed October 11, 1919. Serial No. 329,918.

To all whom it may concern:

Be it known that we, EDWIN CROMPTON and CHARLES L. CROOKS, citizens of the United States, residing at Pueblo, in the 5 county of Pueblo and State of Colorado, have invented certain new and useful Improvements in Locks or Latches; and we do hereby declare the following to be a full, clear, and exact description of the invention, 10 such as will enable others skilled in the art to which it appertains to make and use the same.

This invention relates to locks or latches and more particularly to locks and latches 15 adapted for use on automobile and similar doors, but certain features of novelty and construction herein disclosed may be employed in locks or latches of other types.

In locks and latches it is important that 20 the lock or latch mechanism shall be reliable in operation and readily assembled. A further desirable feature in locks of the type described is that they may be readily operated by the hand used in opening a door 25 carrying the same, and automatically operable when the door is closed. Another desirable feature of such locks or latches is that the locking or latching element thereof shall be positively moved to and from its 30 locking or latching position, instead of depending for such movement on the spring means that carries the locking or latching element, as in the case, for example, of our Patent No. 1,281,144, dated October 8, 1918. 35 A positive retracting and projecting mechanism for the locking or latching element permits the use of a much longer locking or latching knob or head on the locking or latching element, and also permits the use 40 of a much deeper recess to receive such knob, thereby effecting a more secure locking or latching action.

The objects of this invention are therefore to provide a lock or latch mechanism 45 of but few and simple parts which will not readily become disarranged and which may be easily and quickly assembled to reduce the manufacturing cost of such locks or latches. Another object of the invention is 50 to provide a simple positive cam means for manually and automatically moving the locking or latching element to and from its locking or latching positions.

According to the present invention, simplicity of construction and reliability in 55 operation are attained by employing a cam

means that cooperates with a locking or latching element in such a manner as to positively move it to and from its locking or latching position. The cam means may be 60 so designed as to impart a sufficient stroke to the locking or latching element to permit the use of a comparatively long knob on the locking element for engaging in the socket or recess of the keeper. 65

The above and other objects and the novel features of the invention will be apparent from the following description taken in connection with the drawings which illustrate one particularly desirable form in which 70 the principles of the invention may be embodied. In these drawings,

Figure 1 is a vertical sectional view of a lock or latch embodying this invention, parts thereof being shown in elevation, and the 75 lock or latch mechanism being shown in its locking or latching position;

Figure 2 is a similar view, in which the parts of the lock or latch mechanism are shown in unlocked or unlatched position; 80

Figures 3 and 4 are horizontal sectional views of the lock or latch on the lines 3—3 and 4—4 respectively of Figure 1;

Figure 5 is a perspective view of the keeper or strike plate. 85

Referring to the drawing, 10 designates a U-shaped metal lock or latch casing which is open at the rear, top and bottom and has openings 11 and 12 disposed one above the other in its front wall 101, the opening 90 11 being nearer the inner edge of the casing than the lower opening 12. The lock or latch casing 10 is adapted to be fitted in a mortise in an automobile door or the like in such position that the front wall 101 will 95 be substantially flush with the vertical edge of the door and the upper edge of the casing 10 will be sufficiently close to the upper or horizontal edge of the door to bring the button 13 on the operating plunger P within easy reach of an occupant of the automobile. The preferable arrangement is such that the button 13 shall be disposed close to or slightly below the upper edge of the door so that it will not be in the way. 100

When the door is closed, the openings 11 and 12 of the casing 10, respectively, register with the recess 14 and socket 15 in a metal keeper or strike plate K that is suitably fastened in a recess flush with the edge of 110 the cooperating door jamb. The socket 15 is adapted to receive the head or knob 16

of the locking or latching element L, such head or knob projecting through the opening 12 in the front wall of the lock or latch casing. Heretofore, as illustrated, for example, in our Patent No. 1,281,144, the head of the locking or latching element has been made relatively short due to the fact that the movement of the same into the lock or latch casing has depended entirely upon the 10 push given it by a cam means on the keeper plate. We have found that the socket and the cooperating locking or latching knob or head in such locks or latches does not provide a lock or latch that will stay locked or latched under all conditions of service, and accordingly we propose to make the locking or latching head considerably longer and the cooperating locking or latching socket considerably deeper than heretofore, 15 but in order to make this change we find it necessary to positively move it inwardly a sufficient distance to enable the door to be readily closed.

In the construction herein shown, the knob 25 16 of the locking or latching element consists of an elongated cylindrical body portion having a hemispherical outer end that is adapted to seat snugly in the corresponding deep socket 15 in the strike plate K. The rear end of the head 16 has a stem 17 which moves therewith and which is provided intermediate its ends with an elongated through slot 18. Antifriction rollers 30 19 and 20 are rotatably mounted in the slot 18 near the opposite ends thereof, and the head 16 and stem 17 are respectively, supported and guided by suitable means, such means, as herein shown, comprising a flange 121 surrounding the opening 12 and a bracing and guiding plate 21 that bridges and is secured to the side walls of the casing 10. The locking or latching element L is thus mounted in a position to move longitudinally in a horizontal straight line that extends through the center of the socket 15.

Suitable means may be provided for reciprocating the locking or latching element L, that is, positively moving it out of and into locking or latching position at the 50 proper time. We have herein shown a simple arrangement which consists of cam means or elements carried by the plunger or vertically reciprocal operating member P. As illustrated, the cam elements are, for 55 economy and simplicity, formed integral with the plunger P, by stamping the plunger from a single bar with parallel cam edges 22 and 23 extending at an angle to the longitudinal axis of the plunger. At the 60 upper ends of the cam edges or surfaces 22 and 23 there are suitable parallel surfaces or rests 221 and 231. The cam portion of the plunger P extends through the slot 18 and the cam members or surfaces 22 and 23 65 thereof cooperate with the antifriction roll-

ers 19 and 20, respectively, to exert a wedging action to reciprocate the locking or latching members L into and out of locking or latching position, as will be obvious from an inspection of Figures 1 and 2. It will be understood that for some purposes it may be satisfactory to form the cam members separately and secure the same to the plunger in the proper position in some suitable manner, but the arrangement herein shown is more desirable from a manufacturing standpoint. Further, it will be understood that the cam operating means may be employed in some types of locks or latches irrespective of the particular form of knob or slot, antifriction rollers and arrangement of locking or latching element. Suitable means may be provided for retaining the locking or latching element L and its operating member P in the position that they 75 occupy when said element locks or latches the door.

A particularly simple and effective arrangement for accomplishing this purpose is shown in the drawings, but equivalent 90 means may of course be provided for the same purpose. The plunger member P has curved edges or surfaces 222 and 232 which merge into the lower ends of the cam edges 22 and 23. The curved edge 222 is formed 95 as a socket or seat to receive the antifriction roller 19 of the locking or latching element L when the operating member P is in its uppermost position. The parts P and L are thus interlocked, the operating member P 100 being then in a position in which it locks the bolt or locking or latching element L. The edge 232, corresponding but opposite to the edge 222, is so shaped as to engage the other roller 20 on the bolt L, whereby 105 the operating member P maintains engagement with both rollers 19 and 20, preventing lost motion and rattling of the lock or latch parts.

The plunger or operating member P is 110 arranged to reciprocate vertically in openings in the guide and bracing plates 26 and 27 which are secured to the side walls of the lock casing 10. Normally the plunger is yieldingly supported in its upper and locking position by a helical spring 28 that bears at its lower end upon the brace plate 27 and engages a pin 29 or suitable shoulder carried by the plunger.

Suitable means may be provided for automatically operating the plunger P when the door is closed. A desirable and effective means for accomplishing this purpose is herein shown and consists of a rigid arm 30 that extends laterally of the operating member P and may be formed integral therewith and bent inwardly slightly so that its outer end will readily project through the opening 11. The outer end of the arm 30 is of slightly reduced size and constructed to ro- 115 120 125 130

tatably support thereon an antifriction roller 31 that projects through the opening 11 and is adapted to cooperate with a cam edge 32 constituting part of the upper edge 5 of the recess 14 in the strike plate K. The roller 31 is thus positioned in advance of the knob 16 so that the cam surface or edge 32 will engage the roller 31 and begin retracting the knob before the latter reaches 10 the keeper plate K. The cam edge 32 is so shaped as to cause the arm 30 to move the operating member P downwardly as the door is closed, and when the lower edge of the cam surface 32 is reached, by a further 15 closing movement, the roller head 31 is moved into position so that the spring 28 will throw it into the notch 33, thereby locking or latching it and the other parts of the lock or latch mechanism. It will be 20 understood that the automatic downward movement of the operating member P by the cooperation of the cam 32 and the arm 30 is for the purpose of causing the elongated knob 16 to be positively moved or re- 25 tracted from its locking or latching position into the casing a sufficient distance to permit the door to be swung shut without interference of the locking or latching element with the edge of the door jamb. In order to fa- 30 cilitate this operation when the locking or latching knob 16 has not entirely moved into the casing, the keeper plate K may be provided with a cam groove 151 that extends from its outer edge to the socket 15, as illus- 35 trated in Fig. 5, to gradually cam the locking or latching element inwardly in cooperation with the positive means which operates the locking or latching element.

The construction and operation of the 40 lock or latch will be apparent from the foregoing description, the operation being briefly as follows: The parts are assumed to be mounted on a door and door jamb, respectively, in cooperating position, and with 45 the parts in the position shown in Fig. 1, the door is locked or latched. In order to open the door, one hand may be used to engage the button 13 and depress the operating member P against the tension of the spring 50 28, which depression moves the cam 23 downwardly against the roller 20 and the resultant cam action causes the locking or latching element L to move to the right, into the position shown in Fig. 2 in which 55 the roller 20 rides up onto the upper rest 231. Simultaneously, the roller 19 is engaged by the parallel cam 22 and finally moves into position in engagement with the upper rest 221. With the parts in this position, as 60 shown in Fig. 2, the door may be swung open by a slight push, even though the knob 16 may not have been moved entirely into the casing 10. The door having been opened, and the hand having been withdrawn from the button 13, the spring 28

will reciprocate the plunger P upwardly and restore the parts of the lock or latch mechanism to the position shown in Fig. 1, in which the locking or latching knob 13 projects from the lock casing and the roller 31 on the arm 30 is at the upper end of its movement. The arm 30 in this position may abut against the cross brace 26, which latter thereby serves to limit the upward movement of the operating member or plunger P. 75

To close the door without manually operating the lock or latch, the door is swung to closed position and when the projection or roller 31 engages the cam edge 32 of the keeper plate, the operating member P will 80 be moved downwardly automatically, causing the cam 23 to retract the locking or latching member. At the moment that the projection 31 is at the lowest end of the cam 32, and about to snap into the notch 33, the 85 head 16 of the locking element is in position to snap into the socket 15 and the parts are thereupon shot upwardly by the spring 28 from their position in Fig. 2 to the position shown in Fig. 1, the cam 22 in this operation 90 engaging the roller 19 and positively moving the locking or latching element into locking or latching position and in a direction transversely of the movement of the operating member. In the locked or latched 95 position of the head 16, the roller 19 is seated in the recess 222 and the roller 20 is seated in the recess 232, whereby the locking or latching element and its operating means are interlocked by means which will prevent 100 accidental operation of the locking or latching element but which will be readily releasable by manual operation of the operating member.

While we have shown and described the 105 lock or latch mechanism in detail, it will be understood that the lock or latch mechanism and the cooperating parts disclosed are merely illustrative of the broad principles involved and therefore changes may be made 110 in the construction of the same without departing from the spirit of the invention.

What we claim is:

1. In a lock or latch, the combination, with a reciprocable locking or latching element, of an operating member reciprocable transversely of the path of movement of said element, said operating member comprising a handle portion, a stem portion, and cam surfaces intermediate said handle and stem, respectively, adapted to thrust said element in opposite directions, and a spring surrounding said stem and adapted to return said operating member to its normal position. 115

2. In a lock or latch, the combination with a locking or latching element having a recess therein and antifriction means in said recess, of means for operating said element comprising a reciprocable member extend- 120 125 130

- ing through said recess and having cams engaging said anti-friction means to positively move said element to and from its locking position.
5. In a lock or latch, the combination with a locking or latching element, of cams operatively connected thereto and movable transversely thereof for positively moving said element to and from its locking or latching position, and anti-friction means disposed between said element and said cams.
10. In a lock or latch, the combination with a locking or latching element, of cams reciprocable transversely of said element for positively moving the same to and from its locking or latching position, and anti-friction devices carried by said element and disposed between said element and said cams.
15. In a lock or latch, the combination with a reciprocable locking or latching element carrying anti-friction rollers spaced apart longitudinally of said element, and means for operating said element comprising a plunger carrying cams movable transversely of said element between said rollers and resilient means abutting said cams to yieldingly oppose or assist the operation of said plunger.
20. In a lock or latch, the combination with a locking or latching element having a relatively long head adapted to cooperate with a suitable keeper or strike plate, of an operating member comprising cam means arranged to positively move said element from locking or latching position when said operating member is moved in one direction and to move said element into locking or latching position when said member is moved in the opposite direction, an operating handle connected to said operating member, means for releasably retaining said element in its locking or latching position, and spring means opposing the movement of said element from its locking or latching position.
25. In a lock or latch, the combination with a locking or latching element, of a member having integral means for retaining said element in a locking or latching position and integral means for moving said element relatively to its locking or latching position.
30. In a lock or latch, the combination with a casing, of a locking or latching element normally projecting therefrom, cam means for moving said element from and to its locking or latching position, means accessible from the exterior of said casing for manually operating said cam means, and means operable by a keeper or strike plate for operating said cam means.
35. In a lock or latch, the combination with a locking or latching element, of cams mounted therein and having a slot intermediate its ends and a head at its outer end normally projecting from said cas-
- ing, of anti-friction rollers mounted in the ends of said slot, means for moving said element to and from its locking or latching position and releasably retaining said element in its locking or latching position, comprising a reciprocable member having integral cam portions thereon working in said slot and arranged to engage said rollers, an integral extension on said reciprocable member for engaging the head of said element to 70 retain the latter in its locking or latching position, means accessible from outside the casing for manually operating said reciprocable member, means engageable by a keeper or strike plate for depressing said reciprocable member, and means for restoring said reciprocable member to normal position.
40. In a lock or latch the combination with a locking or latching element, or cam operating means therefor movable transversely of the path of said element and adapted to engage the same to move said element to and from its locking or latching position, said locking or latching element and operating means having readily releasable interlocking 80 means adapted to prevent accidental operation of said element.
45. In a lock or latch, the combination with a locking or latching element, of an operating member therefor comprising cam means 85 for engaging means on said locking or latching element to resist accidental operation of the locking or latching element.
50. In a lock or latch, the combination with a locking or latching element carrying antifriction means, of an operating member for said locking or latching element comprising cam means having socket means at 90 one end thereof adapted to receive said antifriction means and interlock said locking or latching element and operating member.
55. In a lock or latch, the combination with a locking or latching element, of means reciprocable transversely of the path of said element for operating the same, such reciprocable means comprising means operable by the cooperating strike-plate in advance of the engagement of such plate by the locking 100 or latching element.
60. In a lock or latch, the combination of a locking or latching element, means reciprocable transversely thereof for operating the same provided with an arm projecting in 110 advance of said element, a co-operating strike-plate provided with a recess, such projecting arm adapted to be actuated by the cooperating strike plate to retract said locking element prior to its registration with its 115 retaining recess in said strike-plate.
65. The combination with a strike-plate having recesses therein, of a lock or latch cooperating with said plate, said lock or latch comprising a casing having openings adapt- 120

ed to register with said recesses, a locking or latching element disposed in said casing and normally projecting from one of said openings, and operating means for said element in said casing and projecting from the other opening therein, said operating means being reciprocal transversely of the path of said element and being adapted and arranged to engage said strike-plate and move said locking or latching element into said casing before the locking or latching element registers with its recess in said plate, and to release said locking or latching element into

its recess in said plate when the locking or latching element registers with its recess. 15

16. In a lock or latch, the combination with a sliding bolt, of means normally dogging said bolt in projected position, means whereby such dogging means may be released and a spring for projecting said bolt 20 and for restoring such releasing means and dogging means to normal position.

In testimony whereof we hereunto affix our signatures.

EDWIN CROMPTON.
CHARLES L. CROOKS.

Certificate of Correction.

It is hereby certified that in Letters Patent No. 1,434,373, granted November 7, 1922, upon the application of Edwin Crompton and Charles L. Crooks, of Pueblo, Colorado, for an improvement in "Locks or Latches," an error appears in the printed specification requiring correction as follows: Page 4, line 84, claim 10, for the word "or", second occurrence, read *of*; and that the said Letters Patent should be read with this correction therein that the same may conform to the record of the case in the Patent Office.

Signed and sealed this 26th day of December, A. D., 1922.

[SEAL.]

KARL FENNING,

Acting Commissioner of Patents.
